Primary Examiner — Paula Greene(74) *Attorney, Agent, or Firm* — Li & Cai Intellectual Property (USA) Office(57) **CLAIM**

The ornamental design for an “earphone adaptor with cable organizer,” as shown and described.

DESCRIPTION

FIG. 1 is a perspective view of an earphone adaptor with cable organizer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view in another visual angle thereof;

FIG. 9 is a perspective view in yet another visual angle thereof;

FIG. 10 is a perspective view showing a practical usage thereof;

FIG. 11 is a perspective view showing the practical usage thereof with an additional earphone;

FIG. 12 is a perspective view showing the practical usage thereof with a clipper;

FIG. 13 is a perspective view showing the practical usage thereof with the additional earphone and the clipper;

FIG. 14 is a perspective view showing a non- usage state thereof with the clipper; and,

FIG. 15 is a perspective view showing the practical usage thereof with a different clipper.

The broken lines depict portions of the earphone adaptor with cable organizer which form no part of the claimed design.

1 Claim, 14 Drawing Sheets---
